UNITED STATES PATENT OFFICE

JOHN Q. SHERMAN, OF DAYTON, OHIO

KEY-HOLE GUARD

Application filed March 15, 1926. Serial No. 94,912.

My invention relates to guards for insertion into the key holes of ordinary door locks and the like, from one side thereof in order to prevent the insertion of a key from the other side, and opening the lock.

There have been in the past various forms advocated for such a purpose, but so far as I am advised these have been uniformly constructed so as to co-operate with the tumblers of the lock, or actually take the place of a key. These old advocated forms have never come into use because of their complication and because they were not adaptable for use with a wide variety of locks.

15 My novel devices are adapted for use with any lock having a key hole plate available from both sides through the familiar key hole, formed with an opening terminating at one end in a hole, or else formed with a key slot having plain walls through which a narrow metal plate can be inserted.

It is my object to clamp or grip a piece of metal in such a position that it cannot be dislodged from the key hole, said metal projecting into the path of any instrument inserted for the purpose of operating the lock from without, or dislodging the key itself, followed by an unauthorized operation of the lock.

30 It is my object to provide as simple as possible a device, which among other things can be packed in a small neat box with other auxiliary devices, and can be operated by following simple directions.

35 I accomplish my objects by that certain construction and arrangement of parts to be hereinafter more specifically pointed out and claimed.

In the drawing:

40 Figure 1 is a perspective view showing my preferred form of device prior to insertion in the key hole.

Figure 2 is a like view showing the device inserted and clamped in place.

45 Figure 3 is an elevation of a door with parts broken away to show my preferred form of guard, as applied.

Figure 4 is a detail of the guard, without the clamp nut, showing a plan view thereof, 50 as applied.

Figure 5 is a detail of the clamp nut.

Figure 6 is a side elevation partly broken away of a modified form of guard.

Figure 7 is a plan view thereof.

Figure 8 is a broken section of a door lock, 55 showing another modified form.

Figure 9 is a perspective of a form of device to be applied when the key is left in the lock.

Figure 10 is a side elevation showing the 60 method of use of the form shown in Figure 9.

Figure 11 is another form of device to be applied directly to the key and serving to prevent dislodgment thereof.

I have shown a lock casing plate 1, with 65 a key hole 2. The device itself is formed as a bar of flat metal 3, having a pair of ears 4, 4, which project laterally intermediate its ends. A round portion of the bar is threaded as at 5, and a clamp nut 6 is provided to fit 70 the threads, this nut having preferably a conical tip 7, and a knurled double rim 8, for easy manipulation by the fingers.

In use the flat tip is inserted into the key hole so that the inserted portion lies in the 75 passageway through which a key 8a would be inserted from the other side of the door. The bar is revolved to bring the two ears into a crosswise position illustrated in plan in Figure 4, and in elevation in Figure 3, 80 so that the bar cannot be dislodged by pushing it inwardly from the outside of the door. The nut is then screwed down tightly against the inner face of the lock plate, thereby holding the device in a clamped position, and 85 entirely free of any danger of being dislodged from without the door.

The tip of the bar does not project out through the other side of the lock plate, but terminates within the lock plate so that a 90 tool could not be applied to twist it off, and it will be impossible to use a master key, or a duplicate key from the outside of the door to bring about an opening thereof.

In Figure 6 and Figure 7 I have shown a 95 device which operates by a wedging action instead of by a screw clamp action. The shank of the device is made by two spring metal plates 10, 10, provided with a knurled head 11. At the inner end they are con- 100

nected by a pin 12 and a pin 13, passing through the two plates mounts a trigger wedge 14. The sides of the plates are turned out at 15 to provide a means to hook inside 5 of the door plate. In use the device is placed inside of the key hole, by compressing the plates.

The wedge is then pushed down at the inner end to get the hooks which have been 10 snapped inside of the lock plate, well spread, and likewise spreading the two bars in the key hole slot. This clamps the plug formed by the two plates, within the lock plate, and prevents insertion of a key by an unauthorized person.

A similar device may be formed of a rod 20, on which are riveted two thin spring plates 21, connected loosely at their inner ends by a pin 22 having a double head, which 20 passes through the rod. The ends of the springs are hooked at 23, and the pin and the hooks act to grip the device in the key hole plate. The plates are compressed at the inner end to allow for the entry of the 25 hooks inside of the key hole slot, and are then permitted to expand. The stud prevents moving of the device in one direction and the hooks prevent movement in the other. Together they keep the rod in place to block 30 the insertion of the key 23a.

In Figure 9 is shown a device for clamping to the key. When the key is inserted in the lock and turned to lock the door, the plate 30 which is formed with a return bent 35 flange 31, is dropped over the key, with the projection 32 extending into the straight part of the slot. The screw 33 in the overhanging flange is then turned down to clamp the device on the shank of the key. The 40 projection 32 prevents the key from being dislodged, since it cannot be revolved away from locking position, due to the presence of the projection in the straight part of the key hole slot.

45 In Figure 11 is shown a spring, which will serve to accomplish the same object as the device in Figure 9.

A spring 40 is set over the shank of the key and screwed onto the shank. It then 50 bears against the head of the key and against the tumbler actuating leaf. When the key is inserted, the spring catches on the key hole and compresses against the head or handle, thus holding the key tight in the 55 lock plate when it has been turned to lock the door.

Having thus described my invention, what I claim as new and desire to secure by Letters Patent, is:—

60 An attachment for a key to prevent the turning thereof within a lock subsequent to the insertion of the key within the lock, comprising a sheet metal member having a return bent flange to laterally engage the 65 shank of the key from above, said member

having a protruding portion adapted to be received within the key hole slot and prevent turning of said member, and means to clamp said member to the key.

JOHN Q. SHERMAN.
